UNITED STATES PATENT OFFICE.

CHARLES J. WITZEL AND GUSTAVE A. HELM, OF BROOKLYN, AND
BENJAMIN W. SMITH, OF NEW YORK, N. Y.

SIDE-RAIL JOINT FOR METALLIC BEDSTEADS.

SPECIFICATION forming part of Letters Patent No. 723,570, dated March 24, 1903.

Application filed October 9, 1902. Serial No. 126,619. (No model.)

To all whom it may concern:

Be it known that we, CHARLES J. WITZEL and GUSTAVE A. HELM, residing at New York, in the borough of Brooklyn, in the county of Kings, and BENJAMIN W. SMITH, residing at New York, in the borough of Manhattan, in the county of New York, State of New York, citizens of the United States, have invented certain new and useful Improvements in Side-
10 Rail Joints for Metallic Bedsteads; and we do hereby declare the following to be a full, clear, and exact description of the invention, such as will enable others skilled in the art to which it appertains to make and use the same.
15 Our invention relates to metallic bedsteads and to means for connecting the head and foot parts of said bedsteads when they are set up for display and exhibition in warerooms and also when set up for use.
20 The object of our invention is to provide a simple and economical means for connecting the side bars with the corner-posts at the head and foot of the bedstead, both the short bars used when the head and foot are set up for
25 exhibition and also the long side bars used when the bedstead is set up for use, and to make the joint between the ends of the side bars and the corner-post in such a manner that play or movement will be prevented and
30 the bars cannot separate from the corner-posts and allow the head and foot to fall.
35 In the accompanying drawings, Figure 1 represents a side elevation of a metallic bedstead in which the corner-posts are connected together by our improved side bars and connections. Fig. 2 is a top plan, on an enlarged scale, of a corner-post, the bracket connected therewith, the ends of the bars, and the joints or connections. Fig. 3 is a side view of the
40 parts shown in Fig. 2. Fig. 4 represents a perspective view of one end of an angular side bar, such as is used when the bedstead is set up for use, and showing our improvements applied thereto. Fig. 5 is a sectional
45 side elevation of a corner-post and bracket with one end of our improved joint and side bar applied thereto. Fig. 6 represents the same with an additional improvement for preventing the side bars from becoming disconnected
50 from the corner-posts.

Referring to the drawings, A B designate

the corner-posts of one side of a metallic bedstead, and C C are the brackets connected with the corner-posts, to which the ends of the side rails are connected. The side rails used 55 to set up the bedstead are either temporary or permanent parts of the bedstead. The temporary bars are merely used to set up the head and foot for exhibition in warerooms, &c., and they are quite short, so that when 60 the head and foot are set up with them they take up but little space, but display the style and quality of the bedstead perfectly. The permanent bars, on the other hand, are full length, so that the bedstead can be set up for 65 use with them. The temporary bar is shown in connection with the corner-posts of one side of a bedstead in Fig. 1. It consists of flat bar D, of metal, having near each end an upright abutment a at right angles to the length 70 of the bar and located at such a distance from the end of the bar as to leave a part of the bar projecting beyond it that forms a lip b. The height of the abutment in this construction is about equal to the thickness of the 75 bracket, so that when the bar is put in place the top of the abutment will be about flush with the upper side of the bracket and the lip will be against the under side of the bracket closely, as shown in Figs. 1 and 3. 80 The abutment and the lip thus form a seat which receives the bracket and the parts of which are parallel, respectively, to the face and under side of the bracket. In the abutment is a bolt-hole d at about the center 85 thereof.

In the bracket C there is a vertical socket or hole e, located a short distance back from its face f, which extends through the bracket from top to bottom, and in the face of the 90 bracket is a slot g, that extends back into the socket or hole e. The width of the slot is about the same as the diameter of the hole d in the abutment, and its position is such that when the bar is in place with the lip b against 95 the under side of the bracket and the abutment against the face thereof the hole d will be in line with the slot g.

Both ends of the side bar and the corner-post brackets are all constructed in the same 100 manner, and the ends of the transverse head-bar E and foot-bar (not shown) and the sides

of the bracket with which they connect may also be constructed in the same manner.

5 F is a bolt having a head *h*, adapted by its shape and size to be placed in the socket *e*, so that its shank *i* will project through the slot *g*, which is adapted to receive a thumb-nut *k*.

When the head and foot are to be set up, the bolt-head is inserted in the socket *e* in one of the brackets—say the head corner-post 10 brackets—with its shank projecting through the slot. One end of the side bar is then properly placed with relation to the bracket and with the shank of the bolt passed through the hole *d* in the abutment, and the thumb-nut 15 *k* being screwed on its projecting end up against the abutment the end of the bar and bracket are firmly and securely joined together.

By screwing the thumb-nut up against the 20 abutment with sufficient force motion or play will be prevented, the head and foot keep perfectly upright, while the lip *b* will prevent the bar and bolt-head from slipping upward and breaking the connection.

25 The above-described mode of connecting the short side bars with the corner-posts is also applied to the full-length angle-bar side rails used to set up bedsteads for general use. In these the ends *L* of the side rails *G* form the 30 abutment, and a projection of the underside of the ends forms the lip *b*, and the inner surface of the ends is squared, so that the thumb-nut can be screwed up against it, as shown in Figs. 4 and 5.

35 In the modification of the invention shown in Fig. 6 an upper projecting lip *b'* is also provided, which projects over the top surface of the bracket. In this construction the lips above and below prevent any vertical movement of the ends of the side bars or rails both 40 upward and downward, and they aid materially in making a strong, firm, and immovable joint. This additional lip may also be applied to the upper ends of the abutments 45 of the short bars.

We claim—

1. Inside-rail joints for bedsteads the combination with a corner-post bracket having a socket in the same and a slot opening from

the socket through the face of the bracket, of 50 a side bar or rail having an abutment provided with a bolt-hole a lip projecting from the abutment under and against the under side of the bracket, and a removable bolt having its head inserted in the socket and its 55 stem passed through the slot in the bracket and the hole in the abutment and secured by a nut, substantially as specified.

2. In side-rail joints for bedsteads the combination with the corner-post bracket having 60 a socket in the same and a slot opening through the face of the bracket, of a side bar or rail having an abutment provided with a bolt-hole lips projecting from the abutment at the top and bottom over the bracket and 65 against the top and bottom of the bracket, and a removable bolt having its head inserted in the socket and its stem passed through the slot and hole in the abutment and secured by a thumb-nut, substantially as specified. 70

3. In side-rail joints for bedsteads the combination with a corner-post bracket having a socket in the same and a slot opening from the socket through the face of the bracket, 75 of a side bar having a seat in its end to receive the bracket formed by an abutment and a lip projecting therefrom, the face of the bracket and the abutment being parallel and the lip projecting over and bearing 80 against the under side of the bracket the abutment being provided with a bolt-hole in line with the slot in the bracket, and, a removable bolt having its head inserted in the socket and its stem passed through the slot 85 in the bracket and the bolt-hole in the abutment and secured by a nut screwed up against the back of the abutment, substantially as specified.

In testimony that we claim the invention 90 above set forth we affix our signatures in presence of two witnesses.

CHARLES J. WITZEL.
GUSTAVE A. HELM.
BENJAMIN W. SMITH.
